To all whom it may concern:

Be it known that I, Paul Haas, a citizen of the
United States of America and residing at 224
East 3rd Street, Emporium, Pennsylvania, have
invented a new, original, and ornamental Design
for an Electron Tube Base or Similar Article, of
which the following is a specification, reference
being had to the accompanying drawing, forming
a part thereof, in which:

Fig. 1 is a perspective view of an electron tube
base or similar article showing my new design.

Fig. 2 is a side elevational view of the metal
base of Fig. 1.

Fig. 3 is a bottom view of the metal base of
Fig. 1.

I claim:

The ornamental design for an electron tube
base or similar article, substantially as shown.

PAUL HAAS.
